UNITED STATES PATENT OFFICE.

ELLIOTT E. FURNEY, OF ST. LOUIS, MISSOURI.

FLYING-MACHINE.

1,090,609.

Specification of Letters Patent. Patented Mar. 17, 1914.

Application filed April 28, 1913. Serial No. 764,087.

To all whom it may concern:

Be it known that I, ELLIOTT E. FURNEY, a citizen of the United States of America, and a resident of the city of St. Louis and 5 State of Missouri, have invented certain new and useful Improvements in Flying-Machines, of which the following is a full, clear, and exact description, reference being had to the accompanying drawings, forming a 10 part of this specification.

My invention relates to a flying machine having wings that are operated in conformity to the movements of flying creatures, such as large fowls and bats.

15 To provide for the attainment of this object, the wings of my flying machine include artificial radius and ulna members, which are the equivalents of the radius and ulna of the wings in the anatomy of the creatures 20 mentioned, and the means for operating the wings include artificial humeri, to which the wings are pinioned, means being provided for causing the pinioned wings to partake of movements corresponding in detail to the 25 movements of the flying creatures imitated in the operation of my flying machine.

Figure I is a top or plan view of a flying machine embodying the features of my invention. Fig. II is a side elevation. Fig. 30 III is an enlarged detail view of fragments of the "radius" and "ulna" wing ribs and one of the transverse wing ribs. Fig. IV is a side elevation, partly in section, of the parts shown in Fig. III. Fig. V is a vertical section taken on the line V—V, Fig. IV. Fig. VI is a vertical section taken on the line VI—VI, Fig. IV. Fig. VII is an enlarged detail top or plan view of the wing operating device shown in Figs. I and II, 40 and the inner portions of the "radius" and "ulna" ribs. Fig. VIII is a side elevation of the parts shown in Fig. VII. Fig. IX is a view similar to Fig. VII, illustrating a modified form of the wing operating device. 45 Fig. X is another view of some of the parts illustrated in Fig. IX, showing them in a different position. Fig. XI is a transverse section taken on the line XI—XI, Fig. IX. Fig. XII is a transverse section taken on the line XII—XII, Fig. IX. Fig. XIII is a dia- 50 grammatical view showing different positions assumed by the "radius" and "ulna" wing ribs. Fig. XIV is a top or plan view similar to Fig. IX, illustrating a further modification. Fig. XV is in part a side ele-

vation and in part a cross section of the modification shown in Fig. XIV.

For the sake of clearness in description and comparison with the flying creatures my flying machine is designed to imitate, I will 60 in the following description of my machine make use of the terms "radius" and "ulna" and of the terms "humerus" and "pinion," with the understanding that these terms are to be understood as applied to artificial members in my machine which have functions corresponding to the functions as found naturally in such flying creatures as I have mentioned.

A designates the car or body of my flying 70 machine, provided with ground wheels 1, and B is the tail or rudder secured to said car or body.

In the preferred form of my invention, shown in Figs. I to VIII, my machine comprises a wing operating shaft C, rotatably mounted in bearings 2 secured to the body A, the said shaft having cranks c, which I shall hereinafter term "humerus" cranks. The means shown for driving said shaft 75 comprises a sprocket wheel 3 secured to said shaft C, a drive chain 4 passing over said sprocket wheel, and a motor 5 for operating said drive chain. "Pinion" spindles 6 carried by the humerus cranks c of the wing operating shaft receive the wings D, as will be hereinafter described. Each wing D comprises longitudinal "radius" and "ulna" ribs 7 and 8 connected at their ends by cross pieces 9, resilient arched transverse ribs 10 80 pivoted to the longitudinal "radius" ribs 7 and loosely fitted to eyes at the upper edge of the longitudinal "ulna" ribs 8, (Figs. III to VI), and guy members 11 connecting the outer ends of the resilient transverse ribs to the longitudinal "ulna" ribs 8. The wing frames thus provided are covered with fabric or any other suitable material, so that the wings are similar in structure to the wings of a fowl or bat, the ribs 7 and 8 acting 85 similar to the radius and ulna of the fowl or bat, and the transverse ribs 10 corresponding to the mid-ribs of wing feathers. At the front inner corners of the wings are transverse members 9 pivoted on the "pinion" spindles or crank pins 6 on which the wings turn. It will be noted that the axes of the "pinion" spindles 6 lie at angles to the axis of the wing operating shaft C, so 90 that the outer ends of the wings will move 100

105

110

in circular paths much larger in diameter than the diameter of the circles described by the "pinion" spindles. In addition to being pivoted to the "pinion" spindles 6, the wings are flexibly connected to the body A by pinioning devices comprising links 12 connected, by ball and socket joints 13, to the said body and connected by similar joints 14 to wing arms 15.

13 The "pinion" spindles 6 move in circular paths around the axis of the "humerus" cranks c; and, during this movement, the wings are guided by the links 12. It will be noted that the wings are carried around 15 in substantially circular paths, and during this movement each wing oscillates about the center of a ball and socket joint 14. The axis of rotation, i. e., the axis of the wing operating shaft C, is fixed with respect to 20 body A, but the location of the axis of oscillation is constantly changing during the operation of the shaft C. The result of this combined rotary and oscillating movement is a motion resembling the movement of the 25 wings of a fowl or bat. The wings swing backwardly and downwardly so as to impel the flying machine forwardly and upwardly, and during the forward movement of the wings, they are spread in a manner to buoy 30 the machine.

My flying machine may be started with a much shorter surface run than is necessary to the starting of aeroplanes, and the positively driven wings will buoy and propel the 35 machine so that it will travel under full control of the operator at elevations close to the ground.

Figs. IX to XIII illustrate a modification in which the wings are supported by the 40 "pinion" spindles 6' and guided by inter-engaging controller wheels 16 and 17, fixed, respectively, to the body and wings of the machine. Each "pinion" spindle 6' is rotatably fitted to a frame consisting of a wing 45 support 18 having arms through which the "pinion" spindle passes, and a sleeve 19 interposed between said arms. The longitudinal "radius" wing rib 7' is rigidly secured to the wing support 18 and the longitudinal "ulna" wing rib 8' is movable 50 about the axis of a hinged pintle 20. Hinge members 21 and 22 connect the pintle 20 to the "radius" and "ulna" ribs 7' and 8', respectively.

55 23 designates an eccentric fixed to the "pinion" spindle 6', and 24 is an eccentric yoke embracing the eccentric 23, said yoke being pivotally mounted on the pintle 20 and rigidly secured to the "ulna" wing rib 8. It will now be understood that a rocking movement of the eccentric yoke 24 will cause the longitudinal "ulna" wing rib 8' to oscillate about the axis of the pintle 20.

To understand the operation of the modification shown in Figs IX to XIII, it should

be carefully noted that the controller wheels 16 and 17 do not rotate. The controller wheels 16 are fixed to the bearings 2' and the controller wheels 17 are fixed to the wing support 18. When the wing operating shaft 70 is rotated, the wheels 17 are tilted so that their teeth successively engage the teeth of the wheels 16. The wheels 17 are loosely mounted on the "pinion" spindles 6', and fixed to the wing supports 18. The angular "pinion" spindles 6' rotate in the wing supports 18 and carry said wing supports in a circular path, but the wing supports 18 are prevented from rotating about the axis of the "pinion" spindles by the controller wheels 16 and 17. The wheels 17 are fixed to the wing supports 18, and these wheels 17 are at all times interlocked with the rigid wheels 16.

While the wing supports 18 and longitudinal "radius" ribs 7' are being carried around in substantially circular paths by the "pinion" spindles 6', the longitudinal "ulna" ribs 8' are oscillated about the axis of the hinge pintles 20. Oscillating movement is imparted to the "ulna" ribs 8' through the medium of the eccentric yokes 24 and eccentrics 23, said yokes being pivoted on the pintles 20 and rigidly secured to the "ulna" ribs 8'.

The wing movement derived from the modification just described is quite similar to the movement obtained from the mechanism shown in Fig. VII. In both of these wing operating devices, portions of the wings are carried around a fixed axis, and at the same time the wings are oscillated about another axis, the location of the axis of oscillation being changeable in response to movements of the wings.

A counterbalance spring 27, (see Fig. IX), surrounds the pintle 20 and is secured at one of its ends to the hinge member 22, the opposite end of said spring being secured to a collar 28 fixed to the pintle 20. 110 The function of the spring 27 is to counterbalance the weight supported by the movable "ulna" rib 8'. The pintle 20 has a non-circular end 29 which may be turned to vary the tension of the spring 27, and, when the desired degree of tension is obtained, the pintle may be locked against rotation by a ratchet 30 and pawl 31, shown most clearly in Figs. IX and XII.

The structure shown in Figs. XIV and XV is similar to that shown in Fig. IX. However, the controller wheels 16 and 17 are replaced by a flexible connection between the wing supports 18' and the body of the flying machine. This flexible connection comprises a pair of forwardly extending arms 32 hinged at 33 to the wing supports 18', arms 34 connected to the arms 32 by pivot pins 35, and upright links 36 connecting the outer ends of the arms 34 to 130

fixed members 37. The function of this flexible connection is to control the wings in a definite path, when the wing operating shaft C' is rotated.

5 I claim:—

1. A flying machine, comprising a body, a power shaft, crank pins carried by said power shaft, wings supported by said crank pins adapted to oscillate about the axes thereof, links, and universal connections joining said links to said wings and body.
- 10 2. A flying machine, comprising a body, a power shaft, crank pins carried by said power shaft, wings supported by said crank pins adapted to oscillate about the axes thereof, said crank pins being at an angle to the axis of said power shaft, links, and universal connections joining said links to said wings and body.
- 15 3. A flying machine comprising a body, wings extending from said body, and wing operating devices connecting the front inner corners of said wings to said body, each,

of said wing operating devices including a power shaft, a crank pin carried by said shaft and extended into the wing so as to constitute a firm support for the wing, and a link, adjacent to said crank pin, forming a support for said wing.

4. A flying machine comprising a body, wings extending from said body, and wing operating devices connecting the front inner corners of said wings to said body, each of said wing operating devices including a power shaft, a crank pin, the axis of which diverges from the axis of said shaft, said crank pin being carried by said shaft and extended into the wing so as to constitute a firm support for the wing, and a link, adjacent to said crank pin, forming a support for said wing.

ELLIOTT E. FURNEY.
